UNITED STATES PATENT OFFICE.

WILLIAM HUKE, OF ST. LOUIS, MISSOURI.

BASKET-FRAME.

1,116,820.

Specification of Letters Patent. Patented Nov. 10, 1914.

Application filed July 31, 1913. Serial No. 782,378.

To all whom it may concern:

Be it known that I, WILLIAM HUKE, a citizen of the United States, residing at 1007-1014 South Seventh street, St. Louis, in the 5 State of Missouri, have invented certain new and useful Improvements in Basket-Frames, of which the following is a description, reference being had to the accompanying drawings, forming a part hereof.

10 My invention relates to the weaving of baskets and has for its object to provide a device by which the weaving of a basket may be facilitated and the basket kept true to form and size.

15 With these and other objects in view my invention consists in the construction and combination of elements hereinafter described and claimed.

Referring to the drawings: Figure 1 is an 20 elevation of a device embodying my invention showing it in expanded form. Fig. 2 is a similar view but showing the device in contracted form. Fig. 3 is a vertical sectional view of the device as shown in Fig. 1; 25 and Fig. 4 is a top plan view of the device as shown in Fig. 1.

In the drawings 1 indicates a bottom plate 30 which may be round, oval, square, oblong or of any form which the bottom of the basket 35 is to have. At suitable intervals about the periphery of this bottom plate are hinged arms 2 preferably of wood bent to the shape which the basket is intended to have. At the center of the bottom plate 2 is erected a 40 rod 3 on which is slidably mounted a sleeve 4 provided with a set screw 5 for holding it at any elevation desired. To a plate 6 carried by this sleeve are pivoted the inner ends of radial arms 7 corresponding in number 45 with the arms 2 and having their outer ends pivoted to these arms.

In the use of the device the bottom of the basket is first woven of the usual splints, rods or osiers and the device is then placed 45 with the bottom plate resting on the woven bottom. The arms 2 are then expanded, if they have not already been expanded, and the weaving of the sides of the basket is pro-

ceeded with, the arms 2 determining the shape and size to be given to it and serving 50 as a form which enables the basket weaver to proceed rapidly and accurately with the work. When the basket is completed the arms 2 are collapsed as shown in Fig. 2 by loosening the set screw 5 and drawing the 55 sleeve 4 upward on the rod 3. The device may then be readily withdrawn from the basket.

It will of course be understood that I do not desire to be limited to the particular 60 construction and arrangement shown.

Having thus described my invention what I claim is:

1. A device for use in weaving baskets comprising a solid bottom plate having its 65 outer face unobstructed, a series of arms pivotally secured thereto and means for holding their free ends in expanded position comprising radial arms, a sleeve to which the radial arms are pivoted and a central rod 70 mounted on the inner face of the bottom plate on which the sleeve is arranged to slide.

2. A device for use in weaving baskets comprising a solid bottom plate having its outer face unobstructed, a series of arms pivotally secured thereto and means for holding their free ends in expanded position comprising radial arms, a sleeve to which the radial arms are pivoted and a central rod 75 mounted on the inner face of the bottom 80 plate on which the sleeve is arranged to slide and means for locking the sleeve on the rod.

3. A device for use in weaving baskets comprising a solid bottom plate having its 85 outer face unobstructed, a series of arms pivotally secured thereto at one end, and means for holding their free ends in adjusted position comprising radial arms, a sleeve adjustably mounted on a central rod to which the 90 radial arms are pivoted, said rod being mounted on the inner face of the bottom plate and extending to the top of the frame only, and means for locking the sleeve on the rod.

4. In a device for use in weaving baskets,

a solid bottom plate having its outer face unobstructed, a series of arms pivotally mounted thereon at a distance one from the other, a series of radial arms secured at one end to the free ends of the first mentioned arms and at their other ends to a sleeve, the sleeve mounted for slidable adjustment on a central rod extending longitudinally through the device and mounted at one end

rigidly to the inner face of the bottom plate, substantially as described.

This specification signed and witnessed this eighth day of July A. D. 1913.

WILLIAM HUKE.

In the presence of—

C. R. SWEENEY,
MATT J. SCHERER.
